(57) **CLAIM**

The ornamental design for a portable power station, as shown and described.

DESCRIPTION

FIG. 1 is a first perspective view of a portable power station showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the portable power station that form no part of the claimed design.

1 Claim, 10 Drawing Sheets
